UNITED STATES PATENT OFFICE.

EDWIN W. SEEGER, OF SOUTH MILWAUKEE, WISCONSIN, ASSIGNOR TO THE CUTLER-HAMMER MFG. CO. OF MILWAUKEE, WISCONSIN, A CORPORATION OF WISCONSIN.

SYSTEM OF CONTROL.

Application filed March 22, 1926. Serial No. 96,401.

This invention relates to systems of control, and, while not limited thereto, is particularly applicable to testing systems for motor controllers.

5 It has heretofore been proposed to equip
motor controllers of various types, and par-
ticularly those of the push button operated
type with means for testing the operation
of the control elements without operating
10 the controlled motor. It has been the usual
practice in such controllers to provide a
manually operated knife switch for inter-
rupting the power connections to the con-
troller during testing, and to also provide
15 for energization of the control elements
through the medium of fuses which are nor-
mally connected between the controller and
said knife switch, but which are capable of
being connected ahead of said knife switch
20 for testing purposes. However, in such con-
trollers it has heretofore been possible after
testing the control elements to leave such
elements in an operative position whereby
the controlled motor is likely to be accidentally
25 restarted upon reclosure of the knife switch.

The present invention has among its objects to provide a controller having improved testing means associated therewith which will prevent accidental starting of the controlled motor after testing of the controller therefor.

35 Another object is to provide an electro-magnetically operated motor controller having testing means associated therewith which insures against starting of the controlled motor after testing of the controller except upon return of the elements of the controller to off position.

Various other objects and advantages of
the invention will hereinafter appear.

The accompanying drawing diagrammatically illustrates an embodiment of the invention which will now be described, it being understood that the embodiment illustrated is susceptible of modification without departing from the spirit and scope of the appended claims.

Referring to the drawing, the same illustrates a motor M to be supplied with current from a direct current circuit indicated by lines L^1 and L^2 through the medium of a manually operated knife switch 1 and electro-magnetically operated contactor 2 . The speed of the motor M is regulated by a rheostat 3 having resistance R^1 and R^2 .

connected in the motor circuit which are adapted to be included and excluded from said circuit in steps by a crosshead 4. Crosshead 4 is operated by a motor *m* having an armature *a* and a series field *f*, and separately operable double pole switches 5 and 6 are provided for selectively establishing reverse power connections for said motor through the medium of fuses 7 and 8. Fuses 7 and 8 are provided with two sets of clips 9 and 10, the former set being arranged to connect said fuses between knife switch 1 and contactor 2, and the latter being arranged to connect said fuses ahead of said knife switch. If desired a double throw switch may be employed instead of two sets of fuse clips to connect the fuses in the aforesaid manner.

The control means further includes a normally open push button 11 and a normally closed push button 12, said push buttons being arranged in the energizing circuit of the operating winding 2^a of contactor 2 and being adapted to control said winding through the medium of a normally closed auxiliary switch 3^a associated with rheostat 3. As hereinafter set forth, switch 2 in responding is adapted to maintain itself in closed position through the medium of auxiliary contacts 2^b and the normally closed push button switch 12 and upon interruption of said maintaining circuit by the latter switch said contactor is adapted to return to off position and can only be reclosed upon return of the rheostat 3 to normal position. Also, the controller includes a normally open push button 13 for controlling the circuit between line L² and one of the fuse clips 10.

The function and operation of the afore-
described controller together with the cir-
cuit connections therefor will now be more
fully described. Assuming that the parts
are in the position shown in the drawing
upon depression of push button 11, the oper-
ating winding 2^a of contactor 2 is energized
by a circuit extending from line L¹ through
fuse 8 by conductors 14 and 15 through the
auxiliary switch 3^a, by conductor 16 through
push buttons 11 and 12, by conductor 17
through the operating winding 2^a and by
conductor 18 through fuse 7 to line L².
Switch 2 in responding maintains itself in
closed position by a circuit extending from
line L¹ through fuse 8 by conductors 14 and

19 through the auxiliary contacts 2^b, by conductor 20 through the normally closed push button 12 and thence through the winding 2^a to line L² as already traced.

- 5 As before stated, the switches 5 and 6 are provided to selectively establish reverse power connections for the crosshead motor *m* and assuming that switch 5 is depressed said motor is energized by a circuit extending from line L¹ through fuse 8, by conductors 14, 15 and 25 through the lower contacts of switch 5, by conductor 26 to and through the armature *a* from left to right, by conductors 27 and 24 through the upper contacts 15 of switch 5, by conductor 28 through field *f* and by conductors 29 and 18 through fuse 9 to line L². Upon release of push button 5 and depression of push button 6 the power connections for the crosshead motor *m* are reversed the same being then established from line L¹ through fuse 8, by conductors 14 and 15 through the upper contacts of switch 6, by conductor 27 through the armature *a* from right to left, by conductors 26 and 30 25 through the lower contacts of switch 6 and by conductors 31 and 28 through field *f* to line L² as already traced. It is thus apparent that switches 5 and 6 provide means for effecting operation of the rheostat in opposite directions and in this connection it should be noted that upon movement of said rheostat out of its normal position, auxiliary switch 3^a is opened whereby the aforescribed energizing circuit for switch 2 can 35 only be re-established upon return of the rheostate cross head 4 to normal position.

The fuses 7 and 8 are normally inserted in the clips 9, but for testing purposes the same are removed from said clips and inserted 40 into clips 10. Also for testing purposes the knife switch 1 is opened to prevent establishment of power connections for the motor M through the medium of contactor 2. With the fuses 7 and 8 inserted in clips 10 the aforescribed energizing circuits may be established to test the operation of contactor 2 and rheostat 3, providing the normally open push button switch 13 is held depressed. Contactor 2 always opens immediately upon 45 release of push button 13 and can only be reclosed upon return of rheostat 3 to normal position. Thus provision is made to prevent accidental starting of the controlled motor upon reclosure of knife switch 1 after 50 testing operations. In practice the push button switch 13 is located at some distance from knife switch 1 to prevent the operator from throwing the knife switch 1 to closed 55 position while maintaining switch 13 in closed position.

In connection with the foregoing it should be noted that the invention is not limited to controllers of the character shown in the drawing. For example, the same may be 60 embodied in controllers having electro-mag-

netic contactors for controlling the starting resistance and may be also used in connection with controllers of the reversing type. However, the invention is particularly applicable to systems of control such as are 70 commonly used in connection with printing presses employing a rheostat of the character shown in the drawing.

What I claim and desire to secure by Letters Patent is:

1. The combination with a controller including an electromagnetically operated control element, of testing means therefor including means for interrupting the line connections for said controller, and means including a normally open switch for establishing an energizing circuit for said control element upon interruption of the line connections for said controller by said former means.

2. The combination with a motor controller including an electromagnetically operated motor controlling element, of means for controlling the line connections for said controller, and testing means for said controller including a normally open switch for establishing an energizing circuit for said element upon interruption of the line connections for said controller by said former means.

3. The combination with a motor controller including a plurality of motor controlling elements, of a switch associated with said controller for controlling the line connections therefor, and testing means for said elements including a testing switch for establishing an energizing circuit for said elements upon opening of said main switch, said testing switch being biased towards open position.

4. The combination with a motor controller including a plurality of electromagnetically operated motor controlling elements, of a main switch associated with said controller for controlling the line connections therefor and testing means for said controller including means for establishing an energizing circuit for said elements upon opening of said main switch and for insuring against response of one of said elements except upon normal positioning of the other of said elements.

5. The combination with a motor controller including an electromagnetically operated main switch and a motor operated rheostat, of a manually operated switch for controlling the line connections for said controller and testing means for said controller including a normally open switch for establishing an energizing circuit for said main switch and the operating motor for said rheostat upon interruption of the line connections for said controller by said main switch.

6. The combination with a motor con-

troller including an electromagnetically operated main switch and a motor operated rheostat, of a manually operated switch for controlling the line connections for said controller and testing means for said controller including a normally open switch for controlling the energizing circuit of said main switch and the operating motor of said rheostat upon opening of said manually operated switch, and means insuring against closure of said main switch except upon normal positioning of said rheostat.

7. The combination with a motor controller, of a switch for controlling the line connections therefor and means for testing said controller upon interruption of said line connections, said latter means including a testing switch located at a point removed from the former switch to prevent simul-

taneous operation of said switches by the operator.

8. The combination with a motor controller including an electromagnetically operated main switch and a motor operated rheostat, of a manually operated switch for controlling the line connections for said controller, a pair of fuses to be included in the energizing circuits of said main switch and the operating motor of said rheostat, means for selectively connecting said fuses between said controller and said manually operated switch, or ahead of said manually operated switch, and means for normally interrupting the circuit through said fuses upon establishment of the latter connections.

In witness whereof, I have hereunto subscribed my name.

EDWIN W. SEEGER.
